SADDLED DINOSAUR AMUSEMENT RIDE DEVICE

Justin J. Bayer, New York, N.Y., assignor to Venride,
Inc., New York, N.Y., a corporation of New York

Filed Feb. 4, 1965, Ser. No. 83,690

Term of patent 3½ years

(Cl. D34—5)

FIG. 1 is a perspective view of my design for a saddled dinosaur amusement ride device;

FIG. 2 is a front view of my design;

FIG. 3 is a rear view of my design; and

FIG. 4 is a plan view of my design.

I claim:

The ornamental design for a saddled dinosaur amusement ride device, substantially as shown.
